(57) **CLAIM**

The ornamental design for a telephone dialing accessory, as shown and described.

DESCRIPTION

FIG. 1 is a top view of a telephone dialing accessory showing my new design;

FIG. 2 is a right side view thereof;

FIG. 3 is a front view thereof;

FIG. 4 is a top perspective view of the nature and environmental use; and,

FIG. 5 is a bottom plan view thereof.

The broken lines throughout the views are for illustrative purposes only and form no part of the claimed design.
